MERCURY SWITCH FLOW INTERLOCK

George Lindley Usselman, Port Jefferson, N. Y.,
assignor to Radio Corporation of America, a
corporation of Delaware

Application January 25, 1936, Serial No. 60,788

8 Claims. (Cl. 200—81)

This invention relates to an improved mercury switch flow interlock which is particularly adapted to a radio transmitter of large capacity.

An object of this invention is to provide a reliable, simple and rugged switch for breaking an electrical circuit when a normally continuous flow of liquid ceases and for closing said circuit when there is normal flow of liquid.

The mercury switch flow interlock of this invention is generally used in connection with some control circuit having relays or contacts which handle the breaking and making of the larger currents and voltages of a radio transmitter. The liquid flow interlock is normally placed in the outlet pipe of the apparatus to be protected for example, in a water cooled vacuum tube. The power being removed from the apparatus in an electrical circuit by the switch when the liquid flow is stopped or falls below a certain predetermined value. The flow interlock of this invention is briefly a chamber in which there is provided a valve seat or nozzle for causing the liquid to form a fountain-like flow which is sufficient in pressure to raise a solid floating member of substantial weight having a rod-like end to operate a small pivoted mercury switch. The solid floating member is arranged with a special contour similar to a water turbine bucket to function with as little retardation to the flow of the liquid as possible.

The invention will best be understood by referring to the accompanying drawings in which:

Figure 1 is a section of the improved flow interlock,

Figure 2 is a side view partly in section of Fig. 1,

Figure 3 is a plan view of Figures 1 and 2,

Figure 4 is a detailed section showing a portion of Figures 1 and 2,

Figure 5 is a detailed section showing a valve for small liquid flows.

Referring now in detail to Figures 1 and 2, the metallic flow chamber 1 is provided with pipe threaded ends 2 and 3 for coupling the chamber with circulating liquid. Substantially in the center of the chamber there is located an orifice 4, the top of which is provided with a valve seat 5. Directly above the orifice an enlarged box-like portion 6 which is provided for receiving the metallic base 7 of a housing 8. The housing 8 comprises a cylindrical wall 9, preferably of transparent glass. The housing 8 is closed at the top by an insulated member 10 of any suitable insulating material such as Bakelite. Members 9 and 10 are secured to base 7

by means of a plurality of metallic rods which are threaded at 12 in base 7 and secured at the upper portion thereof to member 10 by means of suitable screws 13. Centrally located within base 7 is a rod 14 which is threaded at 15 to retain a solid valve or flow interlock element 16 substantially cone-shaped at the portion which normally rests upon the seat 5. It will be noted that the orifice is formed by seat 5, and the shape of the plunger 16, the particular shape shown in Figures 1 and 4 is for efficient operation of large liquid flows, in the order of 8 to 15 gallons per minute. The size, weight and curvature of the plunger may be changed to suit the flow of liquid used. Because of being used in a relatively large flow in this interlock, a large orifice is used and the curvature of the plunger cone is relatively small. This gives sufficient lifting force without retarding the liquid flow to any great extent. Suitably located on the top member 10 are two supporting rods 17 and 18. One of these rods serves the dual purpose of acting as electrical terminals for the switch and also supporting and guide members of the switch. The switch 19 is a mercury switch. This switch is preferably of the type having a pair of contacts suitably arranged within a glass enclosure and contains a small quantity of mercury. When the switch is placed in a horizontal position the mercury causes the contacts to be short circuited and thus completes a short circuit between them. When the switch is tilted on an angle the mercury flows away from the contacts and thus opens the electrical circuit. In order to provide a sensitive and rugged support for the mercury switch a cradle-like member 20 is perpendicularly supported upon the supporting rods 17 and 18. One of the rods 18 is provided with a slot 21 in which a projecting member 22 on the cradle 20 is arranged to engage and prevent the cradle from tilting beyond the correct angle. At the lower end of rods 17 and 18 an insulating baffle and guide member 23 is secured by screws 24 and 25. This member guides rod 14 and also prevents any tendency of the liquid flowing through chamber 1 to splash up into the zone where the mercury switch is located. Electric connections from the mercury switch 19 is made by means of two flexible leads 26 and 27. These flexible leads are provided with suitable flexible insulating members such as glass beads 28 and lead 27 is connected from the lower terminal portion of the mercury switch to rod 18, the upper portion of rod 18 being provided with suitable terminals, nuts 29 55

and 30 and washers 31 and 32. The lead 28 is connected from switch 19 to a terminal screw 33 and terminals nuts 39 and 40 and washers 41 and 42.

5 In Figure 4 there is shown partly in section, the operating portion of the member 16. It will be noted that when the switch 19 is closed the projecting tongue of the cradle is arranged to touch the stop 21 before the mercury switch touches the glass cylinder wall. Also the valve will be fully open when the switch is closed. In order that the upper portion of rod 14 will be electrically insulated from the switch cradle 20, a glass rod preferably of Pyrex glass rod 33 is provided. 10 This rod is rounded over at the top 34 and provides a convenient and good wearing bearing for actuating the switch through a member 35. The entire housing is made air tight by means of suitable gaskets 36 and 37 which are compressed between members 7, 8 and 10 by means of screws 13.

15 The flow interlock shown in Figure 5 is particularly adapted for smaller flows of liquid. As mentioned above, it is desirable to have the interlock function with as little retardation to the flow of liquid as possible. Likewise, with a normal flow of liquid the plunger must push upward with enough force to hold the mercury switch 19 in the closed or horizontal position. To obtain these results the size of the orifice and the curvature of the cone portion of the interlock 20 and its weight must be correctly selected. The flow interlock 40 shown in Figure 5 is particularly adapted for small flows of liquid such as those 25 in the order of 1 to 2 gallons per minute. In this type of interlock the orifice is made adjustable by means of providing different nozzles 41 which are threaded at 42 to the webbed portion of the chamber 43. The plunger 40 is comparatively light in weight and the curvature of the cone shaped face is greater. This gives large 30 lifting force for the small liquid flows.

35 Both types of interlocks shown in Figures 1 and 4 are arranged with adjustable features so that a normal flow of liquid will hold up the plungers 16 and 40 and maintain the mercury switch 19 in a closed position. Also when the liquid flow drops to approximately one-half that of normal or less the plungers will drop sufficiently to open the mercury switch.

40 While only two embodiments of this invention have been disclosed, it is to be distinctly understood that this invention is not to be limited by those shown, but only by such limitations as are 45 clearly imposed in the appended claims.

50 I claim:

55 1. A liquid flow interlock comprising an enclosing chamber, an orifice within said chamber, a cylindrical glass housing above said orifice, a rod 60 supported within said housing, an insulating disc located above said cylindrical glass housing and having secured thereto electrical terminals, a floating member secured to the lower end of said rod, a pivoted enclosed liquid conducting switch 65 located above said rod so as to break an electrical circuit when the normal flow of the liquid decreases to a predetermined value.

70 2. A liquid flow interlock comprising an enclosing chamber, an orifice within said chamber, a housing above said orifice, a rod supported 75 within said housing, a solid floating member secured to the lower end of said rod, an insulating disc located at the top of said housing, two depending rods supported from said insulating disc, a pivoted enclosed liquid conducting switch be-

ing arranged so as to break an electrical circuit when the normal flow of the liquid is reduced to a predetermined value.

3. A liquid flow interlock comprising an enclosing chamber, an orifice within said chamber, a housing above said orifice, a rod supported within said housing, a solid floating member analogous to a water turbine bucket secured to the lower end of said rod, an insulating disc located at the top of said housing, two depending rods supported from said insulating disc, a mercury switch having flexible leads electrically connected to said depending rods, a pivoted enclosed liquid conducting switch being arranged so as to break an electrical circuit when the normal flow 15 of the liquid ceases.

4. A liquid flow interlock comprising an enclosing chamber, an interchangeable nozzle or orifice within said chamber, a housing above said orifice, a rod supported within said housing, a solid floating deflecting member secured to the lower end of said rod, an insulating disc located at the top of said housing, two depending rods supported from said insulating disc, a cradle-like member pivoted to at least one of said rods and supporting an enclosed liquid conducting switch, said cradle member being located above said rod so as to break an electrical circuit when the normal flow 20 of the liquid is reduced.

5. A liquid flow interlock comprising an enclosing chamber, an orifice within said chamber, a housing above said orifice, a rod supported within said housing and located above said orifice, so as to be actuated by the flow of said liquid, a floating member secured to the lower end of said rod, an insulating element located in the upper portion of said housing, depending means supported from said insulating element, a pivoted enclosed liquid conducting switch being arranged so as to be actuated by said rod to break 30 an electrical circuit when the normal flow of the liquid is reduced to a predetermined value.

35 6. A liquid flow interlock comprising an enclosing chamber, an orifice within said chamber, a housing above said orifice, a rod supported within said housing and located above said orifice, so as to be actuated by the flow of said liquid, a floating member having a cone-like end secured to the lower end of said rod, an insulating element located in the upper portion of said housing, depending means supported from said insulating element, a pivoted enclosed liquid conducting switch being arranged so as to be actuated by said rod to break 40 an electrical circuit when the normal flow of the liquid is reduced to a predetermined value.

45 7. A liquid flow interlock comprising an enclosing chamber, an orifice within said chamber, a housing above said orifice, a metallic rod within said housing, a glass rod secured to the upper 60 end of said metallic rod, said metallic rod located above said orifice so as to be actuated by the flow of said liquid, a floating member secured to the lower end of said metallic rod, an insulating element located in the upper portion of said housing, depending means supported from said insulating element, a pivoted enclosed liquid conducting switch being arranged so as to be actuated by the 65 glass rod portion of said metallic rod to break an electrical circuit when the normal flow of the liquid is reduced to a predetermined value.

70 8. A liquid flow interlock comprising an enclosing chamber, an orifice within said chamber, a housing above said orifice, a metallic rod within said housing, a glass rod secured to the upper 75

end of said metallic rod, said metallic rod located above said orifice so as to be actuated by the flow of said liquid, a floating member having a cone-like end secured to the lower end of said metallic rod, an insulating element located in the upper portion of said housing, depending means supported from said insulating element, a

pivoted enclosed liquid conducting switch being arranged so as to be actuated by the glass rod portion of said metallic rod to break an electrical circuit when the normal flow of liquid is reduced to a predetermined value.
